UNITED STATES PATENT OFFICE.

JOHN BRANDWOOD, THOMAS BRANDWOOD, AND JOSEPH BRANDWOOD, OF ELTON,
BURY, ENGLAND.

PROCESS OF AND APPARATUS FOR THE BLEACHING, DYEING, AND ANALOGOUS
TREATMENT OF TEXTILE FIBERS.

Application filed January 24, 1922. Serial No. 531,391.

To all whom it may concern:

Be it known that we, JOHN BRANDWOOD, THOMAS BRANDWOOD, and JOSEPH BRANDWOOD, subjects of the King of Great Britain and Ireland, and residents of Elton, Bury, in the county of Lancaster, England, have invented certain Improvements in Processes of and Apparatus for the Bleaching, Dyeing, and Analogous Treatment of Textile Fibers, of which the following is a specification.

In our co-pending application Serial No. 469,726, we have described and claimed a certain process for the dyeing and analogous treatment of textile fibers in the loose state, that is, prior to spinning, which process consists in passing the material in a belt conveyor through the treatment apparatus and around and over perforated surfaces in the said apparatus, the fluid with which the material is being treated being drawn through the said material held in the conveyor and through the perforations of the before mentioned perforated surfaces. Means are also provided for ensuring that none of the fluid shall pass from the treatment tank through the perforated surfaces without passing through the material being treated, and guide pulleys for the conveyor within the apparatus are also provided.

The present improvements have for object a simplification of the apparatus described in the said application No. 469,726 for carrying out the process referred to, and have for object improvements in the conveyor for carrying the material through the apparatus: improvements in the driving means for said conveyor; a re-arrangement and modification of the perforated surfaces and the means for ensuring that all fluid passing through the perforations of the said surfaces shall pass through the material carried by the conveyor, and the elimination of the guide pulleys within the apparatus.

With these objects in view, our improvements consist of the apparatus to be hereinafter described with reference to the accompanying drawings, in which:—

Fig. 1, is a partly sectional side elevation of the apparatus:

Fig. 2 is a diagrammatic plan of same:

Fig. 3, is a transverse cross section showing a perforated cylinder with its support, and

Fig. 4, is a detail of a combined positive and friction drive for the driving and squeezing rollers of the apparatus.

In Figures 1, 2 and 3, those parts of the apparatus which are not immediately concerned with these present improvements, and those parts which are of already known constructions and capable of being constructed by any person skilled in the art and without special direction, are only indicated or shown diagrammatically.

Referring to Figures 1 and 2, 1 is a tank, which we will hereinafter refer to as the preliminary treatment tank and which may be composed of metal plates or be formed in any convenient and known manner. 2, 3 and 4 are further tanks, hereinafter referred to as the treatment tank, the walls of which are broken away at 5 to show the cylinders and their supports. The transverse partitions between the tanks are provided at their upper ends with inclined plates 6. 7, 8 are pairs of rollers which may be mounted in cheeks, or a framework of known construction situated on either side of the tanks, so said rollers having special means of adjustment as will be hereinafter described.

The material to be treated in the apparatus, say in the process of dyeing, is formed into laps in the scutching machines, and is then placed upon a table having end bearings for the reception of the lap rod necks, as described in our application No. 469,726. The laps are fed as described in the said application, into the nip *x* of two conveyor belts or bands 9, 10, and which are together referred to hereinafter as the conveyor 9, 10. As will be seen on reference to the accompanying drawings, the conveyor belt 9 is endless as is also the conveyor 10, and while they are always together to contain the material under treatment between them while within the apparatus, they separate at the left hand side of the apparatus and return to the nip *x* over the rollers 7 and other rollers specially provided for the purposes.

The cylinders 11 within the preliminary treatment tank and within the treatment tanks proper and around which cylinder the conveyor 9, 10 passes, are formed as shown in section in Figure 3. In that figure 11 is the cylinder proper, provided with perforations 12, which perforations may be of any convenient number and dimensions, and which are formed all over the surface of the cylinder. As will be seen from Figure 3, the cylinder 11 is a sleeve which rotates around and in contact with a cylindrical support. The latter is formed of a central tube 13 and an outer cylindrical shell 14, the inner central tube 13 and the outer shell 14 being connected by spokes 15 for strengthening purposes. Further short radial projections 16 are provided at the lower side of the central tube 13 and these projections connect with a strengthening plate or gusset plate 17 for the ends 18, 18 of the cylinder. Circular orifices 19 shown in Figure 3, are provided in the walls of the lower section of the central tube 13.

The outer face of the cylinder wall 14 is formed with an annular flange or abutment 20. To adjust the cylinder 11 so that it will be in correct sliding relation with the cylinder wall 14, the latter is machined so that the said cylinder will fit therearound without leaving any spaces or interstices between the two surfaces.

In assembling, the cylinder 11 is slid upon the cylinder support 14, until the end thereof abuts against the flange 20. A separate collar 21 is then placed upon the cylinder 14 and slid against the end of the cylinder 11 to a position which will enable the said edge of the cylinder 11 to make sliding contact with the flange or abutment 20 and the inner face of the collar 21, the latter being then secured upon the supporting cylinder in any convenient manner, as for instance by means of bolts or set screws. The ends 18, 18 of the cylindrical support are inwardly flanged so that a complete bearing surface is provided for the ends of the cylinder 11, and those portions of the latter which slide upon these flanges are not perforated. Rotary pumps 23 are connected to the central tube 13 in each case by means of pipes 24, and a further pipe 25 opens communication between each pump and the liquor in each tank, or, when the treatment is to be effected with air, with the atmosphere. Any known or convenient type of rotary pump may be employed. Where all the cylinders and their supports are not in line horizontally, the pipes 24 may be bent pipes as shown at 24^a, Figure 2.

In operating the machine, the material to be treated passes as before indicated into the nip α of the conveyor 9-10 and the said conveyor is drawn through the apparatus by means of the pairs of rollers 7, 8, which are

driven from the fast and loose pulleys 26, 27 through the toothed gearing 28, 29, 30, and 31 the worm shaft 32, the worm wheels 33 and the friction drive shown in Figures 3 and 4. Full details of this combined position and friction drive will be given hereafter. The conveyor after leaving the nip α passes downwards and around the cylinder 11 in the preliminary treatment tank 1 frictional contact of the upper belt 9 of the conveyor 9-10, rotating the sleeve or cylinder 11. The perforations 12 in that portion of the cylinder 11 which is passing at any time over the wall 14 of the supporting cylinder are blocked by the said wall 14, but free access is obtained for the passage of the liquor in the tank 1, to the interior of the cylindrical support through the perforations on that face of the cylinder which is passing from the point y to the point z . Pump 23 therefore draws liquor, from the tank 1 through the perforations 12 which are blocked by the conveyor 9, 10 and the material borne thereby into the cylindrical support, through the orifices 18 into the central tube 13 and thence back to the pump, this treatment being continued while the conveyor slowly passes through the tank and rotate the cylinder 11. By this arrangement therefore the perforations of the cylinder are always completely blocked while the apparatus is in operation; those on the upper portion of the cylinder 11 by the solid wall 14 of the cylindrical support, so that no liquor may pass therethrough; and those on the lower portion of the cylinder 11 by the conveyor and the material carried thereby. Liquor drawn through the perforations 12 on the lower portion of the cylinder 11 must therefore pass through the material in the conveyor.

This preliminary treatment tank may be filled with water for the purpose of allowing the pump to extract therefrom air and waste matters which are always to be found in textile fibers before they have gone through the carding process, and the pump 23 may be of any form found most suitable for the purpose.

From the preliminary tank 1 the conveyor passes with its contained material to the first treatment tank 2, the cylinders of which are of exactly the same construction as that described and shown in Figure 3, with the exception that, as there are three cylinders in this tank, the central cylinder, to allow of the continuous travel of the conveyor 9, 10, has its support reversed, the solid portion 14 of the said support closing the perforations on the lower portion of the rotating cylinder. The dimensions of the solid portions of the cylindrical supports in this three-fold arrangement of cylinders in one tank are such that as the conveyor 9, 10 leaves the first cylinder 11, the angle it forms with the next cylinder will not uncover any

perforations which are not blocked or closed by the wall 14 of either of the cylindrical supports.

Various treatments may be given to the material in the conveyor 9, 10 as it passes through the various tanks, such treatments, being, by way of example, preliminary clearing treatment in tank 1 as mentioned, dyeing, washing off, and air treatment or oxidizing, but any form of liquor or air treatment or other treatment, by means of pumps, in any sequence, and for which the apparatus is suitable, may be effected therein.

One or more or all of the pairs of rollers 7, 8 may be mounted as shown in Figure 1, to the left of that figure. The lower roller 8 is mounted in a fixed bearing 34 and the upper roller 7 is mounted in a bearing block 35 which engages with and is adapted to slide vertically between the side cheeks 36 of the frame. On a lug 37 of one cheek 36 is pivoted the lever 38, which is pivotally connected by means of a link 39, the length of which is adjustable by the turn-buckle 40, to the lower lever 41 fulcrumed at 42 and bearing the counterweight 43. The upper lever 38 bears at 44 a tapped nut (not shown) through which the threaded spindle 45 passes and which spindle rotatably engages at its lower end with the bracket 46 on the adjustable bearing block 35. The spindle 45 is provided with the hand wheel 47. By this construction high frictional contact of the rollers 7, 8 with the conveyor 9, 10 is assured, as the counterweight 43 through its connections always exerts pressure upon the upper roller 7 by reason of the sliding bearing 35, while allowing the said upper roller to yield should any undue thickness of the conveyor at any point demand such yielding. At the same time the threaded spindle 45 permits of positive adjustment of the rollers of a pair in relation to each other, to suit the thickness of material which it is decided at any time to pass through the apparatus.

In order to maintain the necessary tautness of the upper conveyor belt 9 of the conveyor 9, 10, we may mount a gravity roller 48 in bearings 49 adapted to slide freely within the side frames 50. One of these frames, with the necessary bearing block, is provided at each side of the machine, and the upward movement of the bearing 49 in its guide is limited by the screw down member 51 adjustable by means of the threaded spindle 52 and the hand-wheel 53. One or more of these gravity rollers, with the adjusting members referred to, may be employed.

The lower conveyor belt 10 of the conveyor 9, 10 on its return from the outlet end of the machine to the nip α , may pass over rollers 54 fitted in bearings in any known manner below the bottom of the

tanks as shown. To allow of this, the tanks are supported at their opposite ends on brick or concrete or other suitable blocks 55. The bottom of each tank however is in communication with a sump preferably below the floor and formed to allow of easy drainage of waste liquor, the supporting pillars 55 being employed for the tanks as shown. As adjusting means for the lower belt conveyor, two brackets 56 are bolted or otherwise secured at either end of the apparatus, each of said brackets being slotted to receive and allow to slide therein a bearing 57 in which the adjusting rollers 58 are journalled. A threaded spindle 59 engages within an interiority threaded orifice in each bracket and is rotatably secured to the bearing block 57, so that by inserting a bar in the tommy holes 60 the bearing block 57 may be adjusted as desired within the slot, to tighten or slacken the conveyor belt.

In Figure 4 is shown to a larger scale than the other figures the details of the special drive for the pairs of rollers 7, 8, to give an efficient drive and at the same time to allow the rollers 7, 8 to slip should too great a thickness of material be presented to them in the conveyor 9, 10, such capability of slipping avoiding damage to the said conveyor and consequent possible waste of material. In Figure 4, 32 is the worm shaft, driven as indicated in Figure 1, and 33 a worm wheel meshing with the said shaft. These members are of usual construction and are merely indicated diagrammatically in the figure. The worm wheel 33 meshes with a corresponding spur wheel on the shaft 32 and is formed with a hollow boss 61 and is mounted on the roller shaft 62 so that it may rotate freely thereon. On the boss or sleeve 61 or compounded with the worm wheel 33 is the friction disc 63 making frictional contact with another friction disc 64 these discs being preferably formed as shown, that is, the driving faces are formed of annular rings secured to the discs no engagement of the disc 63, 64 taking place near the centre thereof. The disc 64 is keyed upon the roller shaft 62, and on the said roller shaft is keyed a spur wheel 65 meshing with a spur wheel of the same diameter keyed to the shaft 66 of the upper roller 7. A spring 67 and hand-wheel 68 are employed to regulate the pressure of the faces of the discs 63 and 64. On rotation of the worm wheel 33, which is as stated loose on the shaft 62 the friction disc 63 also rotates and by its contact with the driving face of the friction disc 64 rotates the shaft 62 to which the friction disc 64 is secured. The lower roller 8 is thus rotated and the spur wheel 65 keyed on the shaft 62 communicates its movement to the upper roller 7 through the spur wheel 69.

keyed on the shaft 66. Each roller therefore has at all times the same speed of revolution. Should the material in the conveyor 9, 10 be by inadvertance too thick 5 to allow the said conveyor to pass between the rollers 7, 8 and the rollers be thereby slowed down, slipping will take place between the faces of the discs 63 and 64 and damage to the conveyor be thereby prevented. 10 70, 71 are the brushing off rollers and brackets for removing the material from the lower conveyor 10 as it separates from the upper conveyor 9, in the manner described in co-pending application Serial 15 No. 469,726.

What we claim as our invention and desire to secure by Letters Patent is:—

1. In an apparatus for treating textile fabrics, the combination of a plurality of 20 rotatable perforated cylinders each supported upon a fixed central bearing adapted to cover some of the perforations in the cylinder as the latter rotates around said bearing, and a conveyor passing over said 25 cylinders and adapted to cover the remaining perforations thereof.

2. In an apparatus for treating textile fabrics, the combination of a plurality of 30 rotatable perforated cylinders, a support for each of said cylinders comprising a stationary tubular member adapted to admit a fluid to the interior of said cylinder, and means carried by said support for covering a portion of the interior surface of the cylinder thereby to prevent escape of the fluid 35 through the perforations at said portion.

3. In an apparatus for treating textile fabrics, the combination of a plurality of 40 rotatable perforated cylinders, a support for each of said cylinders comprising a stationary tubular member adapted to admit a fluid to the interior of said cylinder, means carried by said support for covering a portion 45 of the interior surface of the cylinder thereby to prevent escape of the fluid through the perforations at said portion, and a conveyor comprising a pair of traveling belts adapted to carry between them the material to be treated and to engage the cylinders so

that said material covers the portion of the 50 cylinder which is not covered by the interior covering.

4. In an apparatus for treating textile fabrics, the combination of a plurality of 55 rotatable perforated cylinders, a support for each of said cylinders comprising a stationary tubular member adapted to admit a fluid to the interior of said cylinder, means carried by said support for covering a portion 60 of the interior surface of the cylinder thereby to prevent escape of the fluid through the perforations at said portion, a conveyor comprising a pair of traveling belts adapted to carry between them the material to be treated and to engage the cylinders so that 65 said material covers the portion of the cylinder which is not covered by the interior covering, pairs of driven rollers yieldingly engaging said belts thereby to cause the same to travel with the contained material in contact with successive cylinders, and means for adjusting the frictional engagement of 70 said rollers with said belts.

5. In an apparatus of the class described, the combination of a pair of belts, pairs of 75 driven rollers engaging said belts for causing travel of the latter, one of each pair of rollers being mounted for sliding movement toward and from the other, and gravity operated means for yieldingly urging the 80 slidable roller toward its companion roller.

6. In an apparatus of the class described, the combination of a pair of belts, pairs of 85 driven rollers engaging said belts for causing travel of the latter, one of each pair of rollers being mounted for sliding movement toward and from the other, gravity operated means for yieldingly urging the slid- 90 able roller toward its companion roller, and manually operated means for adjusting said 95 frictional engagement of the rollers with the belts.

In testimony whereof we have hereunto set our hands.

JOHN BRANDWOOD.
THOMAS BRANDWOOD.
JOSEPH BRANDWOOD.
